CLAIM

The ornamental design for gum wrapper, as shown and described.

DESCRIPTION

FIG. 1 is a perspective view of a gum wrapper embodying my design;

FIG. 2 is a front view thereof;

FIG. 3 is a rear view thereof;

FIG. 4 is a top view thereof; and,

FIG. 5 is a right side view thereof, the left side being a mirror image of the right side.

The bottom of the gum wrapper forms no part of the claimed design.
